UNITED STATES PATENT OFFICE.

NATALIE MARJORIE BARLET, OF PHILADELPHIA, PENNSYLVANIA, ASSIGNOR TO THE JUNOFORM COMPANY, OF PHILADELPHIA, PENNSYLVANIA, A CORPORATION OF PENNSYLVANIA.

SANITARY NAPKIN.

1,150,572.

Specification of Letters Patent. Patented Aug. 17, 1915.

Application filed August 26, 1913. Serial No. 786,677.

To all whom it may concern:

Be it known that I, NATALIE MARJORIE BARLET, a citizen of the United States, residing at Philadelphia, in the county of 5 Philadelphia and State of Pennsylvania, have invented new and useful Improvements in Sanitary Napkins, of which the following is a specification.

This invention relates to improvements in 10 catamenial bandages and it consists of a catamenial bandage with a supporting band and a waterproof backing united together by said supporting band, by means of registering slots formed in the bandage and the 15 waterproof backing, through which the supporting band is extended substantially as hereinafter more fully disclosed and defined by the appended claims.

Figure 1 is a perspective view showing 20 the underside of the catamenial bandage and the interlocking detachable connection of the supporting band therewith. Fig. 2 is a perspective view showing the absorbent element of the bandage unfolded to illustrate 25 the three plies thereof and also the slots formed in the end portions of the absorbent element to receive the supporting band. Fig. 3 is a perspective view of the waterproof backing. Fig. 4 is a perspective view 30 of the supporting band. Fig. 5 is a detail transverse sectional view taken on line 5—5 of Fig. 1.

Referring to the accompanying drawings 35 illustrating the practical embodiment of the invention 5 designates the absorbent element of the improved catamenial bandage, 6 the waterproof backing element, and 7 the supporting band.

The absorbent element 5 may be made of 40 any suitable material and may be made up in any suitable manner, in the drawings a flat sheet is illustrated, which sheet is provided with two parallel longitudinal fold lines 5^a and 5^b, whereby three plies 5^c, 5^d, and 5^e, are provided, which are adapted to lie in folded contacting relation, as shown 45 in Figs. 1 and 5. The opposite end portions of each ply of the absorbent element are provided with transversely extending slots 5^f, the slots in the different plies being so arranged that they will register with one another when the sheet is folded. The waterproof backing 6 is also provided with trans-

verse slots 8', located near the ends thereof and adapted to register with the slots 8 of 55 the absorbent element 5.

In assembling the bandage the absorbent sheet or element is folded upon itself so that the slots 8 are brought into registering positions, the waterproof backing 6 is laid on 60 one side of the absorbent element, with the slots 8' thereof in register with the slots 8, and the supporting band 7 is interlocked 65 with the absorbent element and the waterproof backing by extending the end portions thereof through the slots 8' and 8, as clearly disclosed in Figs. 1 and 5.

By the construction described it will be seen that no tension is placed on the absorbent element or upon the waterproof backing, as the supporting band is in no way positively connected to either element and said band receives all the pull and tension. This avoids gathering the bandage, or causing 70 it to stretch, with consequent discomfort and imperfect action. When it is desired to adjust the position of the catamenial bandage it is not necessary to disconnect the supporting band from the sanitary belt to which it is connected by the usual 75 safety pins, or by other like devices, as the absorbent element and the waterproof back can be moved on the supporting belt by simply sliding said elements thereon. This is a material advantage, as readjustment can 80 be easily made whenever the necessity for it arises, without embarrassment. Another 85 vital advantage secured is that there is no danger of the supporting band tearing away from the absorbent element, with the consequent discomfort and embarrassment.

Having described my invention I desire to 90 secure by Letters Patent:

1. A catamenial bandage comprising an absorbent element folded to provide a plurality of plies, each ply having end portions provided with slots, the slots of the plies being adapted to register, and a supporting band disposed centrally and lengthwise against the bottom side of the absorbent element and extended through the registering slots.

2. A catamenial bandage comprising an absorbent element folded to provide three plies and having registering slots in the ends 105 of the plies, a waterproof backing element

having slots to register with the slots of the absorbent element, and a supporting band disposed midway of the side edges of the absorbent element and extended slidably 5 and detachably through said slots and adapted to hold the three elements named united.

In testimony whereof I have hereunto set my hand in presence of two subscribing witnesses.

N. MARJORIE BARLET.
